LOCOMOTIVE FIREBOX

Gust J. Christenson, Chicago, Ill., assignor to
 Locomotive Firebox Company, Chicago, Ill., a
 corporation of Delaware

Application June 13, 1936, Serial No. 85,063

3 Claims. (Cl. 122—68)

This invention relates to improvements in locomotive type fireboxes and it consists of the matters hereinafter described and more particularly pointed out in the appended claims.

One of the objects of the present invention is to provide a locomotive type firebox with a novel tube arrangement for increasing the heating surface of the firebox and for accelerating the water circulating action by siphoning water from points along the side water legs and discharging the same upon the top of the crown sheet to insure a constant flooding of the same.

Another object of the invention is to provide a circulating tube arrangement for a firebox of this kind wherein the use of longer tubes is possible not only to give a greater heating surface area, but also to make them more flexible so that they will accommodate, without cracking, the relative movement of certain of the firebox sheets under temperature changes.

A further object of the invention is to provide in a locomotive type of firebox, a circulator tube arrangement providing a better support for the brick of the arch and whereby a lesser number of brick patterns is required and wherein the brick may be so arranged as to produce a tighter arch.

The above mentioned objects of the invention, as well as others, together with the advantages thereof will more fully appear as the specification proceeds.

In the drawing:

Fig. 1 is a longitudinal vertical sectional view through a locomotive firebox and adjacent boiler parts, embodying the preferred form of the invention, the plane of the section being taken on the line 1—1 of Fig. 2;

Fig. 2 is a transverse vertical sectional view through the same as taken on the line 2—2 of Fig. 1; and

Fig. 3 is a detail horizontal sectional view on a somewhat enlarged scale as taken on the line 3—3 of Fig. 2.

Referring now in detail to that embodiment of the invention, illustrated in the accompanying drawing, 5—5 indicates the side sheets of the firebox, 6 indicates the crown sheet, 7 indicates the front or flue sheet and 8 indicates the back sheet thereof. It will be understood that the firebox is positioned in the rear end of the associated boiler shell, which includes the outer side sheets 9—9, top sheet 10, back sheet 11 and front throat sheet 12. Portions of the back sheets 8 and 11 respectively, are formed to provide a fuel door opening 13.

Several of the various sheets mentioned coact

to form the side water legs 14, back water leg 15 and front throat 16 respectively, all bottomed by a mud ring 17. The above is typical of a conventional locomotive boiler rear end structure and requires no further detailed description except to say that companion sheets are suitably staybolted.

To increase the effective evaporating surface area of the firebox and the steaming and water circulating efficiency of the associated boiler, I provide the following arrangement:

On each side of the longitudinal median line of the firebox are located sets of water evaporating and circulating tubes 18—18 with the tubes in each set arranged in spaced relation, longitudinally of the firebox. Preferably the tubes in one set are disposed in the transverse planes of those in the other set.

Each tube includes an inlet portion 19, an outlet portion 20 and an intermediate connecting portion 21 of a reverse curve formation on the order of an ogee. The inlet portion 19 has an extremity 22 arranged at a right angle to the plane of the associated side sheet 5. This extremity opens through and is fixed in said side sheet and merges into the inlet portion by a short curved portion 23. The inlet portion 19 which as shown herein is relatively straight, extends upwardly and inwardly from the curved portion 23 at an inclination desired in the associated part of a fire arch which will be referred to later. The crown sheet 6 is arched or curved transversely of the firebox and the outlet portion 20 of the tube extends radially with respect thereto and opens through and is fixed therein in any suitable manner.

As herein shown, the intermediate portion 21 of the tube comprises upper and lower reversed curved parts and the lower curved parts of the tubes in both sets are spaced relatively close together as best appears in Fig. 2.

It is apparent that with the tubes anchored in the crown sheet and side sheets as mentioned, forces are transmitted through said tubes from the crown sheet to the side sheets. Due to the reverse curve or bulging formation of the intermediate portions 21 of the tubes, these portions flex to accommodate such relative movement between the sheets without cracking.

While the spacing between the lower curved parts of the intermediate portions of the tubes is relatively close, it is so gauged as to never permit actual contact between said parts.

The structure admirably coacts to support an arch indicated as a whole as at 24 in Fig. 2.

This arch is made up of transverse rows of brick, each including an outer end brick 25, an inner end brick 26 and intermediate brick 27. The bricks are preferably curved transversely to the plane of the row in which they are positioned, as appears in Fig. 1. Each brick has concaved corners 28 to rest upon upper parts of the tubes. The outer end brick abut against the associated side sheet 5 and the inner end face of the inner end brick of the row is bevelled off to provide a full face contact with the like face of the inner end brick of the opposed row of brick. Each inner end brick is cutaway as at 29 to reduce its width to permit it to pass the curved intermediate parts of the tubes, as best appears in Fig. 3.

In the front end row of bricks, the bricks thereof rest at one side upon the frontmost tubes and at the other side engage upon lugs 30 on the flue sheet 7 below the lowermost fire tube or flue 20 therein.

In the outer side sheets 9-9, in line with the inlet end extremities 22 of the tubes are wash-out plugs 31 and in the top sheet 10 of the boiler shell, in line with the outlet ends 20 of the tubes, 25 are wash-out plugs 32.

In the operation of the boiler, of which the firebox forms a part, the tubes absorb heat units from the products of combustion. Due to the thermic heads thus produced, water and steam 30 are discharged through the outlet ends into the boiler water space above the crown sheet, and water is drawn into the tubes from the side water legs 14, at longitudinally spaced points therein. Thus a continuous circulatory action is estab- 35 lished, the influence of which is exerted in all directions in the side water legs so as to produce a turbulence therein which prevents settling out of the solids in the water at the bottom of the side water legs. Also, due to the gushing or dis- 40 charge of water from the outlet end of the tubes, a constant flooding of the crown sheet is effected that insures its complete submergence. Thus even though the water level in the boiler falls below normal, it is assured that the same will at 45 all times be covered with water.

Again, due to the increased circulation of water through the side water legs, the stresses normally imposed on the side sheets of the firebox are equalized and this of course increases the life of 50 said sheets.

The tubes which are preferably made of seamless metal, may be readily bent to shape without cracking and may be easily installed in place.

While in describing the invention, I have referred in detail to the form, arrangement and construction of the parts thereof, the same is to be considered only in the illustrative sense so

that I do not wish to be limited thereto except as may be specifically set forth in the appended claims.

I claim as my invention:

1. A locomotive firebox embodying therein a 5 crown sheet and side sheets, a set of circulator tubes arranged on each side of the longitudinal median line of the crown sheet, each tube including an inlet end portion opening through an associated side sheet, an outlet end portion opening 10 through the crown sheet and an intermediate portion of reverse curvature connecting said inlet and outlet end portions, the intermediate portions of the tubes in one set substantially abutting the like portions of the tubes in the other set near the 15 longitudinal median line of the firebox, and arch brick supported on the inlet end portions of the tubes in both sets and meeting on said line.

2. A locomotive firebox embodying therein a 20 crown sheet and side sheets, a set of circulator tubes arranged on each side of the longitudinal median line of the crown sheet, each tube including an inlet end portion opening through an associated side sheet, an outlet end portion opening 25 through the crown sheet and an intermediate portion of reverse curvature connecting said inlet and outlet end portions, the intermediate portions of the tubes in one set being disposed in substantially close relation to the intermediate portions of the tubes in the other set near the 30 longitudinal median line of the firebox, and arch brick supported on said inlet end portions and parts of said intermediate portions of the tubes 35 of both sets and meeting in the longitudinal median line of the firebox to form a closed arch. 35

3. A locomotive firebox embodying therein a 40 crown sheet and side sheets, a set of circulator tubes arranged on each side of the longitudinal median line of the crown sheet, each tube including an inlet end portion opening through an associated side sheet, an outlet end portion opening 45 through the crown sheet and an intermediate portion of reverse curvature connecting said inlet and outlet end portions, the intermediate portion of the tubes in one set being disposed in sub- 50 stantially close relation to the intermediate portion of the tubes in the other set near the longitudinal median line of the firebox, the tubes in each set being successively longer as they approach the front of the firebox and the inlet ends 55 of the tubes in each set opening through the associated side sheet at successively lower points toward the front end of the firebox, and arch brick supported on said inlet end portions and parts of said intermediate portions of the tubes 55 of both sets.

GUST J. CHRISTENSON.
